US0D1006959S

(12) **United States Design Patent** (10) **Patent No.:** **US D1,006,959 S**
(45) **Date of Patent:** **** Dec. 5, 2023**

(54) **ADJUSTABLE PRESSURE REGULATOR**

(71) Applicant: **Ningbo Xuri Xinghua Measurement and Control Equipment Co., Ltd., Zhejiang (CN)**

(72) Inventor: **Minbiao Chen, Zhejiang (CN)**

(73) Assignee: **Ningbo Xuri Xinghua Measurement and Control Equipment Co., Ltd., Zhejiang (CN)**

(**) Term: **15 Years**

(21) Appl. No.: **29/747,668**

(22) Filed: **Aug. 24, 2020**

(51) **LOC (14) Cl. 23-01**

(52) **U.S. Cl. USPC D23/235**

(58) **Field of Classification Search**

USPC D23/235, 233, 246, 245, 249
CPC F16K 31/365; F16K 17/085; F16K 31/126;
F16K 1/126

(57) **CLAIM**

The ornamental design for an adjustable pressure regulator, as shown and described.

DESCRIPTION

FIG. 1 is a perspective view of an adjustable pressure regulator, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings depict environmental structure and boundaries and form no part of the claimed design.
